UNITED STATES PATENT OFFICE

CARLOS WETZELL, OF FRIEDENAU, NEAR BERLIN, AND WALTHER INHOFFEN, OF WILMERSDORF, NEAR BERLIN, GERMANY, ASSIGNORS TO N. V. INTERNATIONALE AUTOMATEN MAATSCHAPPIJ, LA, LANGE VOORHOUT, OF DEN HAAG, HOLLAND

COIN-CONTROLLED VENDING APPARATUS

Application filed August 29, 1927, Serial No. 216,242, and in Germany September 6, 1926.

The present invention relates to improvements in coin controlled vending machines. More especially the invention relates to means for preventing the removal of goods 5 from a coin controlled vending apparatus by means of false coins of a lower weight than the genuine coins for which the machine is designed.

In accordance with the invention an ejecting device is provided, by means of which false coins of cardboard, pressed goods, fibre, light metal, sheet metal etc., of less weight than the genuine coins required, are stopped, caught and ejected. For this purpose the 10 coin conduit is equipped with a device which is arranged at the end of a balanced testing lever and which initially catches all 15 coins falling through the said conduit. If a coin has the prescribed weight, it will 20 rock the said device out of the coin conduit and the coin will then drop into operative position. If however a false coin of less 25 weight than prescribed is inserted into the apparatus, the weight of such coin will not be sufficient to move the catching device out 30 of the path of the coin, wherefore the latter will slide over an inclined face arranged on the catching device and be ejected through an opening arranged adjacent said face.

A constructional form of the invention is shown by way of example in the accompanying drawing, in which

Fig. 1 is a sectional view through the inlet chute or conduit of the coin, with the other mechanisms removed.

Fig. 2 is a diagrammatic or outline face view of the chute.

Fig. 3 is a section on line 3—3, Fig. 1.

40 Fig. 4 is a front or face view of a preferred form of base plate according to the invention.

Fig. 5 is a vertical section on line 5—5, Fig. 4.

45 In the coin conduit 5 a catching arm or device 39 (Figs. 1—3) is arranged at one end of a lever 40, which is pivotally supported at 41 and by means of which the catching device can be swung outside the coin conduit. In the walls of the coin conduit a

small opening 42 and a larger opening 43 are arranged on opposite sides of the catching device. The arm of the lever 40 remote from the catching device is preferably formed or loaded at its free end 44 in such 55 a manner that it represents a certain definite weight and can only be moved out of position when a genuine coin operates the catching device, at which time said device moves backward through the opening 42. 60 The lower end 45 of the catching device normally extends into the larger opening 43 and is inclined or offset. At the top of the coin conduit an inlet slot for the coins is arranged in known manner. A collecting 65 chamber 46 for false coins is arranged at the outside of the coin conduit 5.

The apparatus operates in the following manner:

When a coin is dropped into the coin 70 conduit it is at first stopped by the catching device 39 at the end of the testing lever 40. If the coin is genuine its weight will rock the lever 40 in clockwise direction and move the catching device 39, 45 out of the 75 coin conduit through the opening 42, so that the said coin can drop into operative position.

If however the coin is a false one and of 80 less weight than prescribed, it will not be able to rock the testing lever but will slide off the inclined deflecting end 45 of the catching device and drop into the collecting space or chamber 46 through the opening 85 43. In this way it will be seen that the apparatus is protected against unlawful removal of goods by means of false coins of less weight than genuine ones.

According to Figs. 4 and 5, the base plate 31 to which the casing 1 of the apparatus proper (represented in dotted lines in Fig. 5) is to be fastened, is fixed to a wall, the back of a chair or the like by means of screws 34 in such a manner that the screws are covered when the apparatus is in place. 95 Neither the apparatus nor the base plate can therefore be unlawfully removed from its place of location.

The base plate 31 is equipped with pins 29 having heads with a considerably greater 100

diameter than their stems. The pins are adapted to cooperate with key-hole or other suitably formed slots 27, 33 and 27', 33' in the casing 1 and form with said slots a kind of bayonet-joint connection. The base plate 31 further possesses an upstanding rim or flange 47 of greater extent than the pins 29.

In order to bring the casing 1 into the position which it normally is to occupy, it is placed on the base plate within the confines of flange 47 and, for instance, turned to the left until the pins 29 automatically move into the wide parts 27 and 27' of the slots, whereupon it is turned back slightly to conduct said pins into the narrow parts 33 and 33' of the slots which will catch behind the heads of the pins and retain the casing on the base plate. Thereafter the casing can be locked to the base plate by means of a separate locking device (not shown).

The base plate may, besides the vending apparatus proper, also carry various other objects which are useful in connection with the articles to be vended. If, for instance, soap is stored in the apparatus a mirror could be fastened to the base plate; if cigars or cigarettes are sold, a match box or holder could be arranged on the said plate etc. In this way it will not be necessary to fasten the mirror etc. to the supporting wall by means of special screws or the like whereby the wall is damaged. The mirror or other object may be detachably connected to the base plate or be rigidly fastened to the same. If it is detachably connected to the base plate it is suitably secured against unlawful removal by means of the same locking device which locks the casing 1 to the base plate 31 and can in such case be detached from the base plate without it being necessary to loosen the same from its support wall.

We claim:

1. A controlling mechanism for vending machines, comprising a coin chute having openings in its front and rear walls located substantially opposite each other; a pivoted balance lever; and a depending catching arm secured to one end of said lever and projecting through the rear chute opening into the interior of the chute to be struck and thereby rocked backward through said opening by a coin falling through the chute; said catching arm having a deflecting member at its lower end for ejecting a coin of insufficient weight through the front opening in the chute.

2. A controlling mechanism for vending machines, comprising a coin chute having openings in its front and rear walls located substantially opposite each other; a pivoted balance lever; and a depending catching arm secured to one end of said lever and projecting through the rear chute opening into the

interior of the chute to be struck and thereby rocked backward through said opening by a coin falling through the chute; said catching arm having its free lower end inclined toward and normally extending into the lower portion of the front chute opening so as to deflect therethrough a coin of insufficient weight.

3. A controlling mechanism for vending machines, comprising a vertical coin chute having a relatively-narrow vertical opening in its rear wall and a relatively-wide vertical opening in its front wall substantially opposite the first opening; a normally-horizontal balance lever pivoted intermediate its ends and having one end weighted; and a depending catching arm secured to the other end of the lever and extending through the rear chute opening into the interior of the chute to be struck and thereby rocked backward through said opening by a coin falling through the chute and to eject a coin of insufficient weight through the front opening in the chute.
